(57) **CLAIM**

The ornamental design for a foldable step stool, as shown and described.

DESCRIPTION

FIG. 1 is a front perspective view of a foldable step stool;
 FIG. 2 is a rear elevational view thereof;
 FIG. 3 is a front elevational view thereof;
 FIG. 4 is a left side elevational view thereof;
 FIG. 5 is right side elevational view thereof;
 FIG. 6 is a top view thereof;
 FIG. 7 is a bottom view thereof; and,
 FIG. 8 is a bottom perspective view thereof.
 The broken lines shown in the drawing views are included for the purpose of illustrating environmental structure and form no part of the claimed design.

1 Claim, 8 Drawing Sheets(56)
